BOLSTER DAMPING ARRANGEMENT FOR RAILWAY CAR TRUCKS

Cal W. Wulff, Elmhurst, Ill., assignor to Holland Company, a corporation of Illinois

Application July 1, 1957, Serial No. 669,368

9 Claims. (Cl. 105—197)

This invention relates to a bolster damping arrangement for controlling the movement of a bolster relative to its supporting side frame and, more particularly, it is concerned with a high-strength bolster end construction which accommodates and cooperates with a novel form of friction-producing system that acts upon the opposed vertical friction surfaces provided on the side frame columns that flank the bolster.

The principal objects of the present invention are to provide a bolster damping arrangement wherein the bolster end construction provides internal housings of maximum size that are arranged to reinforce and strengthen the bolster end construction; wherein friction blocks are mounted in the housings for limited floating movement to permit them to maintain continuous flush engagement with the side frame; wherein the control springs that load the blocks are free to flex along their entire length in following the movements of the friction blocks; and wherein the movable parts of the friction system are retained compressed for handling, shipping, and installation of the bolster.

Briefly, this is accomplished by providing straight-sided, longitudinally and transversely extending vertical walls in the ends of the bolster with the walls extending between the usual top and bottom walls of the bolster to form large-sized internal housings arranged in back-to-back relationship and reinforcing the bolster ends. Each housing receives a friction block with a controlled clearance to permit the desired controlled or limited floating of the friction block for maintaining flush contact with the friction surface on the side frame columns. The friction block and the transverse walls of the housing provide spring seats for engaging only the end or dead coils of the control spring so that all of the live coils of the spring are completely free to flex. This relationship not only insures that the block will continuously maintain flush engagement with the friction surface on the side frame, even during moments when the bolster and side frame are slightly out-of-square, but it also eliminates the buildup of harmful stress concentrations in the control spring itself.

A novel arrangement is provided for retaining the parts of the friction system, and this includes a retention arm extending rearwardly from the middle of the friction block and through the center of the control spring to project through a central relief opening provided in the transverse housing wall that forms the seat for the control spring. The rear end of the retention arm is slotted to receive a retainer key.

Other objects and advantages of the invention will become apparent during the course of the following description.

In the accompanying drawings forming a part of this specification and in which like numerals are employed to designate like parts throughout the same,

Fig. 1 is a fragmentary side-elevational view of a freight car truck equipped with a bolster damping ar-

2

rangement according to the invention, with parts of the truck broken away to better illustrate the construction of the friction-producing apparatus and its housing;

Fig. 2 is an elevational view of one of the housings as seen from its open outer end;

Fig. 3 is an enlarged, fragmentary top plan view through the housing portion of the bolster, with parts broken away and sectioned;

Fig. 4 is a view corresponding to the right half of Fig. 3 but illustrating the parts compressed to receive a retaining key;

Fig. 5 is a perspective view of the friction block construction and illustrates the seating relationship between the control spring and the friction block;

Fig. 6 is a side elevational view of a forked-type tool for compressing the parts of the friction-producing apparatus to facilitate the insertion of the retaining key; and

Fig. 7 is a plan sectional view corresponding to the view at the right half of Fig. 3 and illustrating a modified friction block construction.

Referring now to Fig. 1, there is shown a conventional side frame 10 of a freight car truck. The side frame includes an upper compression member 11, a lower tension member (not shown), and spaced side columns 12 that define a bolster opening 13 within which the truck bolster, generally designated 14, is received for relative vertical movement. The bolster is supported on a plurality of springs 15, which rest upon spring seats (not shown) at the bottom of the bolster opening 13.

The general arrangement of the bolster 14 is familiar and comprises top and bottom walls, numbered 17 and 18 respectively, and side walls 19 having the usual outboard and inboard guide flanges 20 that cooperate with the side frame columns 12 to restrain the bolster against endwise movement.

A pair of internal housings 21 are formed in back-to-back relationship at each of the opposite ends of the bolster, and they are arranged to receive the friction-producing apparatus, which is loaded against the opposed vertical friction surfaces on suitable wear plates 23 that are mounted on the opposing faces of the side frame columns 12.

As best seen in Figs. 1, 2 and 3, the walls defining the internal housings 21 are preferably cast integrally with the bolster, and the top and bottom walls of the bolster serve as the top and bottom walls of these housings. With this arrangement, the housings are of maximum size.

Each housing is defined by longitudinally extending inboard and outboard vertical side walls 24 and 25, respectively, and a transversely extending vertical rear wall 26 that connects the side walls. All of these walls extend the full height of the bolster to rigidly connect the top and bottom bolster walls, and this arrangement presents a remarkably high-strength bolster end construction. The side walls 24 and 25 are offset transversely (see Fig. 3) so that their outer ends form an enlarged housing in which the friction block 28 is disposed and so that their inner ends define a housing that accommodates the control springs 29 for free lateral flexing movement. The inner ends of the side walls are preferably formed with the usual inspection slots 27.

The preferred form of friction block is best seen in Fig. 5, and it comprises a flat front wall 30, portions of the periphery of which are formed with integral rearwardly extending cornered guide wings 31, the opposite sides of which extend adjacent to and surround the spring seat surface provided on the rear face of the friction block. The guide wings give the block a maximum depth of $1\frac{1}{8}$ ", but as indicated at 32, the portions of the guide

wings adjacent to the control spring are bevelled to avoid conflict with the active coils of the control spring.

According to the invention, a controlled clearance is provided between the friction block and its housing. For example, in the disclosed form, the housing for the friction block may be $5\frac{3}{8}$ " wide and $4\frac{1}{2}$ " high, while the corresponding dimensions of the friction block are $\frac{1}{16}$ " less. This limited clearance arrangement between the block and its restraining housing permits a controlled or limited floating action of the block to enable the block to tilt as necessary and maintain flush engagement with the friction surfaces on the wear plates. Under certain running conditions, such as when the car is negotiating curves and one side of the truck tends to run ahead of the other or when the brakes are so sharply applied as to produce tilting of the bolster, the relationship between the side frames and the bolster becomes slightly out-of-square, and if the block is to maintain a full, flat-surfaced bearing engagement with the wear plate, it must realign itself within its housing. The controlled clearance concept of the present invention allows sufficient free-floating movement of the block to compensate for such out-of-square conditions.

The present arrangement is to be distinguished, however, from instances where the friction block merely happens to be loosely mounted in its housing since, in the present case, the control spring is confined only at its opposite ends where the dead coils engage spring seats that are so arranged as to permit all desired free-flexing movement of the active coils of the control spring. Thus, as the friction block adjusts in its housing, the control spring flexes along its entire length as it follows the movements of the friction block, and severe stress concentrations, which inevitably lead to control spring failure, are avoided.

To permit this free flexing, the ends of the guide wings of the friction block are bevelled, as mentioned previously, to prevent contact with the active coils at the outer end of the control spring while at the inner end of the control spring, this concept is carried out by providing an upwardly facing arcuate support flange 34 that fixes the position of the dead end coil of the control spring 29, which actually seats against the rear transverse wall 26. Preferably, the flange includes an outwardly extending ramp 35 that facilitates the insertion and positioning of the control spring. Attention is directed to the fact that at all points, the internal housing provides sufficient clearance to avoid contact with the active coils of the control spring.

As described thus far, the invention contemplates a floating friction block loaded by a control spring that is free to flex along its entire length, with the parts being mounted in internal housings of maximum size in order to accommodate large-diameter control springs. The larger the control spring, the lower its stress and, hence, the longer its life. Further, the greater the spring diameter, the greater is the bearing area that is subjected to spring pressures and, hence, the more uniform are the resultant pressures. Another advantage accruing from a floating friction block arrangement is concerned with the fact that the bolster-damping action does not come into play during certain low-energy shocks which produce only very limited vertical movement of the bolster. Under normal running conditions, a limited clearance, as indicated at the region 36 in Fig. 1, will exist between the top of the friction block 28 and the underneath surface of the top wall 17 of the bolster; and when low-energy shocks depress the bolster against the cushioning action of the springs 15, the bolster will move down independently of the friction block so long as the bolster movement does not exceed this limited clearance; therefore, all such bolster movements will be cushioned only by the springs 15 and no shocks will be delivered to the car as would be the case if the friction-damping system were brought into play immediately.

While the principles of the invention may be embodied in a bolster-damping arrangement that utilizes an adjustable spring seat, such as shown in co-pending application, Serial No. 564,294, filed February 8, 1956, now Patent No. 2,896,550, the disclosure of which, to the extent it is not inconsistent herewith, is specifically incorporated by reference, it is preferred to embody the invention in an arrangement wherein the parts of the friction-producing apparatus are retained in compressed condition during installation of the bolster by a suitable retaining element which holds the friction block in a retracted position against the expansive action of the compressed control spring.

In this preferred form of the invention, the friction block includes an integral rearwardly extending central retention member 38, with the retention member projecting through a relief opening 39 formed in the rear transverse wall 26 of the housing. It will be noted from an inspection of Figs. 1 and 3 that the relief opening provides a substantial clearance for the retention member to accommodate the tilting movement of the friction block. This central retention arrangement utilizes the otherwise dead space at the center of the control spring so that the size of the control spring need not be reduced to accommodate the retaining arrangement. Furthermore, the retaining member itself may be of appreciable size and, hence, of great strength.

In addition to the above advantages, an axially positioned retention member directs the forces of retraction along the axis of the control spring to produce uniform retraction of the friction block and thereby eliminate tipping of the friction block and reduce the actual distance and, hence, effort, required to realize complete disengagement between the friction block and its wear plate. Also, off-axis bending stresses on the control spring are avoided and this also increases control spring life.

At its rear end the retention member 38 is provided with a horizontal slot 40, defined by a bevelled rear surface 41, so that the retaining key 42 engages only the peaked mid-point of the surface 41 and thus acts directly along the axis of the control spring. As shown in Fig. 4, the retaining key may be provided with a wedge-shaped leading edge 43 to permit the key to be sledge-driven into place. An alternative and preferred manner for retracting the friction block is to employ the fork-shaped tool 44 shown in Fig. 6, which may be used for retracting the block sufficiently to permit the retaining key to be inserted manually. For this purpose the retention member 38 is provided with vertically extending nubs 46 and the transverse rear wall 26 is cast with the upper and lower fulcrum projections 47, best seen in Fig. 1, so that the arms 48 of the retraction tool will straddle the end of the retention member as the tool is inserted into the position shown in Fig. 4. The use of the retainer tool has the advantage that it eliminates the necessity of driving the retainer key 42 with a sledge. This is not only an unpleasant task, but it subjects the key and retention member to unnecessary damage and may cause failures at inconvenient times and locations.

The central retention member 38 of the friction block, while preferably integral, could, of course, be formed separately and rigidly affixed to the friction block by a threaded connection or by welding or by a suitable pinning arrangement. Alternatively, the retention member and friction block could be connected through a ball and socket connection, and this would allow free movement of the friction block relative to the retainer, in which case the retainer may be arranged for a sliding fit in the relief opening at the rear of the housing.

Still another friction block retention arrangement is shown in the plan sectional view of Fig. 7 wherein the friction block 28' and the retention member 38' are separately formed and are provided with cooperating spherically-shaped surfaces, designated 50 and 51 respectively, to allow all necessary out-of-square movements

of the friction block without, however, disturbing the control spring. This arrangement has the additional advantage that the friction block may be removed and replaced independently of the retaining mechanism and also the relief opening 39' in the rear wall 26 may provide a sliding fit with the retention arm 38' for guiding the same.

It should be understood that the description of the preferred form of the invention is for the purpose of complying with section 112, Title 35, of the U.S. Code.

I claim:

1. In a railway car truck including a side frame having longitudinally spaced columns providing opposed vertical friction surfaces and a bolster resiliently supported between said columns and having side walls facing said surfaces, said bolster being provided with opposed internal housings opening outwardly toward said friction surfaces to form aligned openings in said side walls, said internal housings each receiving a control spring and a friction block with the control springs urging the friction blocks through said aligned openings into engagement with said friction surfaces; said internal housings each being formed by transversely spaced, longitudinally extending inboard and outboard side walls offset away from each other adjacent their outer ends, and a transversely extending rear wall formed with a spring seat for said control spring and a relief opening surrounded by and centered in said spring seat, said rear wall connecting said housing side walls, each of said friction blocks having a spring seat for the outer end of its control spring and including a rearwardly projecting central retention member telescoped through said central spring to project through said relief opening with the rearmost portion of said retention member having a retaining slot extending transversely therethrough and cooperating with a retaining key that is gripped between the rear of said slot and said transverse rear wall to retain the friction block.

2. In a railway car truck including a side frame having longitudinally spaced columns providing opposed vertical friction surfaces and a bolster resiliently supported between said columns and having side walls facing said surfaces, said bolster being provided with opposed internal housings opening outwardly toward said friction surfaces to form aligned openings in said side walls, said internal housings each receiving a control spring and a friction block with the control springs urging the friction blocks through said aligned openings into engagement with said friction surfaces; said internal housings each being formed by transversely spaced, longitudinally extending inboard and outboard side walls offset away from each other adjacent their outer ends, and a transversely extending rear wall connecting said housing side walls and forming a seat for said control spring, each housing being formed at its lower inner end with an upwardly facing, concave surface spaced above the bottom of the housing to border the lower periphery of the seat on the adjacent transverse rear wall to engage the dead inner end coil of said control spring and support and center the same in said housing, each of said friction blocks being slightly smaller in cross-sectional area and corresponding in cross-sectional shape to said housings for limited floating movement therein, each block providing a spring seat for the outer dead end coil of its control spring with the housing walls providing lateral clearance for the active coils of its control spring to accommodate free-flexing movement between the ends of said spring as it follows the floating movement of its friction block.

3. In a bolster damping arrangement for use in a railway car truck that includes a side frame having spaced columns providing flat, opposed vertical friction faces and a bolster resiliently supported between said columns and having side walls facing said columns, said bolster carrying opposed internal housings disposed between said friction faces and opening outwardly through said side walls to form aligned openings therein, and a friction-

producing apparatus in each housing, each apparatus including a control spring and a flat-faced friction block with the control springs urging the friction blocks through said aligned openings into flat-faced engagement with said friction faces; the improvement wherein each housing is defined by a transverse rear wall formed with a central relief opening and each friction block includes a rearwardly extending central retention member telescoped through said control spring and having its rearmost portion projecting through said relief opening and formed with a retaining slot, and a retaining key in each slot and gripped between the rear end of its slot and the rear surface of the adjacent transverse rear wall to retain each friction block.

4. The arrangement of claim 3 wherein the rear surface of each transverse wall carries vertically spaced fulcrum projections outboard of said relief opening and each retention member carries upper and lower external nubs at its rear end that overlap vertically with said projections.

5. In a bolster damping arrangement for use in a railway car truck that includes a side frame having spaced columns providing flat, opposed vertical friction faces and a bolster resiliently supported between said columns and having side walls facing said columns, said bolster carrying opposed internal housings disposed between said friction faces and opening outwardly through said side walls to form aligned openings therein, and a friction-producing apparatus in each housing, each apparatus including a control spring and a flat-faced friction block with the control springs urging the friction blocks through said aligned openings into flat-faced engagement with said friction faces; the improvement wherein each housing is defined by a transverse rear wall formed with a central relief opening and a separate spring seat for said control spring is disposed between said control spring and said friction block, said separate spring seat and said friction block having complementary, spherically-shaped surfaces accommodating universal relative pivotal movement therebetween, said spring seat including a rearwardly extending central retention member telescoped through said control spring and having its rearmost portion projecting through said relief opening and formed with a retaining slot, and a retaining key in each slot and gripped between the rear end of its slot and the rear surface of the adjacent transverse rear wall to retain each separate spring seat.

6. In a bolster damping arrangement for use in a railway car truck that includes a bolster having side, top, and bottom walls, said bolster having each of its ends resiliently supported for vertical movement between side frame columns that flank the bolster opening, with a friction producing apparatus incorporated in each bolster end for cooperative engagement with a vertical friction surface provided on the adjacent side frame column, each bolster end having internal walls forming a housing that defines a chamber opening outwardly through the side wall of the bolster and each friction producing apparatus including a control spring and a flat faced friction block with the control spring urging the friction block outwardly through the chamber into flat faced engagement with the friction surface of the adjacent side frame column, the improvement wherein each housing has a transverse rear wall bounding the chamber defined thereby, said transverse wall having an opening therethrough, each friction block includes a rearwardly extending retention member projecting axially through its control spring and having a rearmost portion projecting through said relief opening and terminating in structure having an abutment facing toward said rear wall, said abutment cooperating with a retaining member that is gripped between the abutment and said wall to retain the friction block retracted within its housing.

7. A friction block comprising a substantially flat base plate having a flat front friction surface of rectangular

configuration and a rear spring seat surface, right-angle guide wings at each corner of said block and extending along the marginal edges thereof to partially surround said spring seat surface with opposed portions of adjacent ones of said wings being immediately adjacent said spring seat surface and being bevelled to slant towards said base plate, said block including a retention member projecting rearwardly from the center of said base plate and terminating in structure having a forwardly facing abutment that is disposed rearwardly of the maximum rearward extension of said wings.

8. In a railway car truck of the type having a side frame provided with a bolster opening defined in part by a side frame column: the combination with a bolster having side, top and bottom walls, said bolster being supported in said bolster opening for cushioned movement therein, one of the side walls of the bolster having an opening therein at a point adjacent and facing said column; of friction-producing apparatus mounted on said one side wall for frictionally engaging the column to dampen movement of the bolster, said friction-producing apparatus comprising wall structure fixed within said bolster to form a housing rigid with said bolster and having a transverse wall at its inner end and having an open outer end in register with said wall opening, said transverse wall having a relief opening centrally therein, a coil spring in said housing and seated against said transverse wall at points surrounding the opening therein, a friction block at the outer end of said housing and urged towards engagement with said column by said spring and including an inwardly extending retention member projecting lengthwise through the spring and the relief opening and terminating in structure having an abutment facing toward said transverse rear wall, and a retaining member engageable between said abutment and said transverse rear wall to retain the friction block retracted within the housing.

9. In a railway car truck of the type having a side frame provided with a bolster opening defined in part by a side frame column: the combination with a bolster hav-

ing side, top and bottom walls, said bolster being supported in said bolster opening for cushioned movement therein, one of the side walls of the bolster having an opening therein at a point adjacent and facing said column; of friction-producing apparatus mounted on said one side wall for frictionally engaging the column to dampen movement of the bolster, said friction-producing apparatus comprising wall structure fixed within said bolster to form a housing rigid with said bolster and having a transverse wall at its inner end and having an open outer end in register with said wall opening, said transverse wall having a relief opening centrally therein, a coil spring in said housing and seated against said transverse wall at points surrounding the opening therein, a friction block at the outer end of said housing and urged towards engagement with said column by said spring, said friction block corresponding in cross-sectional shape to said housing and having an overall clearance dimension in all transverse directions within its housing on the order of $\frac{1}{16}$ " for limited following movement therein, said block including an inwardly extending retention member projecting lengthwise through the spring and the relief opening and terminating in structure having an abutment facing toward said transverse rear wall, said transverse rear wall and said friction block each having structure providing a spring seat for contacting only the end coil at the corresponding end of the control spring, said housing providing lateral clearance for the remaining coils of the control spring to accommodate free flexing movement between the ends of said spring as it follows the floating movement of its friction block, and a retaining member engageable between said abutment and said transverse rear wall to retain the friction block retracted within the housing.
